(57) **CLAIM**

The ornamental design for a cabinet as shown and described.

DESCRIPTION

FIG. 1 is a top, front perspective view of a cabinet showing my new design:

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, bottom perspective view thereof.

The broken lines in the drawings depict portions of the cabinet that form no part of the claimed design. The broken lines in the drawings indicate enlarged portions which form no part of the claimed design.

1 Claim, 8 Drawing Sheets

FIG. 1

FIG. 2

FIG. 3

FIG. 4

FIG. 5

FIG. 6

FIG. 7

FIG. 8
